CABINET

Nat Levenberg, Lynbrook, N. Y.

Application February 11, 1955, Serial No. 34,480

Term of patent 3½ years

(Cl. D33—19)

The figure is a perspective view of a cabinet showing my new design.

The elongated door and drawer handles are conventional as indicated by the broken lines.

The back of the cabinet is plain and the side of the cabinet not shown is substantially the same in appearance as the side shown.

I claim:

The ornamental design for a cabinet, substantially as shown and described.
